UNITED STATES PATENT OFFICE.

ADDAMS S. McALLISTER, OF NEW YORK, N. Y.

ALTERNATING-CURRENT MACHINERY.

No. 851,828.

Specification of Letters Patent.

Patented April 30, 1907.

Application filed April 2, 1906. Serial No. 309,481.

To all whom it may concern:

Be it known that I, ADDAMS STRATTON McALLISTER, a citizen of the United States, residing at New York, in the county of New York and State of New York, have invented certain new and useful Improvements in Alternating-Current Machinery, of which the following is a specification.

My invention relates to alternating current machines of the commutator type; and its object is to provide a method and apparatus for preventing sparking at the commutator brushes.

Commutation in alternating current machines presents difficulties which are absent in direct current machines, since in an alternating current machine the coil, which is short-circuited at the instant of commutation, is subject to an alternating or pulsating field. Even when the armature is stationary there exists an appreciable electro-motive force between terminals of each coil under the brushes due to the "transformer" action of the field flux, the field acting as the primary and the short-circuited armature coils as the secondary of a transformer. When a brush passes from one commutator segment to the next, as the armature rotates, the electro-motive force is ordinarily short-circuited through the brush which completes the connection between the segments. The current which flows through this short-circuit is of large value and produces an excessive heating of the brush, the segments and the coil. Moreover, the rupture of this current produces destructive arcing at the brushes, and its presence is, in general, detrimental to the perfect performance of the machine. To the evil effects of this local current in the short-circuited coils may be attributed the slow progress which has been made in the development of the commutator type of alternating current machines.

Various methods of reducing sparking have been devised. It has been proposed to use resistance in the armature leads in order to limit the value of the local short-circuit current and motors embodying this idea have been constructed which have operated satisfactorily. It is evident, however, that the resistance in the armature leads to be of any value, must absorb an appreciable amount of energy, due both to the local current and to the normal useful current passing through the armature. Practical requirements demand that these resistances shall be of limited

cross-section, entailing the constant danger that they will burn out, and, furthermore, they must be placed in a position where it is difficult to make repairs or to replace them in case they are burnt out.

My present invention provides a method by which the sparking may be decreased to any desired extent, a minimum of ohmic resistance may be employed, and such resistance may be placed in an easily accessible location external to the machine.

My invention will be best understood by reference to the accompanying drawings, in which—

Figure 1 shows diagrammatically a dynamo or motor arranged to show certain features of the invention; Fig. 2 shows the same with the armature rotated to a different position; Fig. 3 shows the complete arrangement of my invention applied to a machine, the armature being in a position intermediate to that of Figs. 1 and 2; Fig. 4 shows a modification thereof; and Fig. 5 shows a top plan view of a commutator with the brushes in cross-section.

The machine may be bipolar or multipolar and may have the field winding F, arranged as a distributed or a concentrated winding and connected in any desired manner. The armature A, may be of any type such as those now well known in direct-current practice and the coils may be arranged in lap or wave winding, the terminals of the coils being connected directly to the commutator segments without the interposition of resistance in the leads. The live segments a, and the insulating segments b, of the commutator, may be approximately equal in width though this is not absolutely necessary.

Instead of using a single brush or set of inter-connected brushes, at each point of commutation as usual, I employ three independently insulated brushes for each set, each brush having a width somewhat less than the width of each dead or insulating segment. Two of the brushes, viz; the outer brushes 1, 3, are connected to the terminals of a reactance coil L, while the middle brush 2, is connected to the middle point of the reactance coil and to a terminal of the machine by means of conductors l₁ l₂.

The operation of the arrangement above described will be better understood by referring to Figs. 1, 2 and 3. In Fig. 1, it will be observed that the only current which can flow in the local circuit of the armature coil

under the brushes 1, 3, and the reactance coil L, is the exciting or magnetizing current of the reactance coil, which is practically a negligible quantity. The main power current flowing through the armature passes differentially through the halves of the reactance coil in opposite directions and hence causes no opposing reactance. That is, for the power or line current the coil L opposes no reactance but for the local short-circuited current it acts like a true reactance coil to choke or decrease the current to a negligible quantity. In Fig. 2, the brushes 1 and 3, bear upon insulating segments b, and therefore receive no current whatever, while brush 2 is in contact with a live segment a, and transmits the entire power or line current. It is evident that either in the position shown in Fig. 1, or that shown in Fig. 2, the machine is devoid of any short-circuiting effect and no abnormal heating will be produced at any point. Fig. 3 shows the brushes in a position on the commutator intermediate between that of Fig. 1, and Fig. 2, which is the most disadvantageous position during the operation of the machine. Brushes 1 and 2, are in contact with one live segment while brush 3 contacts with another segment. Since brushes 1 and 3 are on different segments and are connected through the reactance coil L, no direct short-circuit exists between them, the electro-motive force of one armature coil being, however, impressed upon the terminals of the reactance coil. Since the brush 2 is connected to the middle point of the reactance coil through conductors l_1 l_2 , there exists between brush 2 and said middle point an alternating electro-motive force having a value equal to one half of that of one armature coil, which would tend to circulate a current locally through brushes 1 and 2 and one half of the reactance coil. In order that this short-circuited current may be kept within proper limits, adjustable resistances r_1 , r_2 , are inserted in the conductors l_1 , l_2 , between brush 2 and the middle point of the coil L. It will be observed that these resistances are in series for the local short-circuit current, but are in parallel for the normal useful armature or line current. These resistances are made of ample current carrying capacity for the maximum load of the machine and are, therefore, not subject to burn outs. Moreover, they are external to the armature and can be easily adjusted or repaired.

Although perfect commutation requires the resistances r_1 , r_2 , to have an appreciable ohmic resistance, it is to be noted that the leads between the armature and the usual controller C, necessarily possess an appreciable resistance, and that by the use of two leads as shown at l_1 , l_2 , which are always in series for the short-circuit current but are used either singly or in parallel for the nor-

mal armature current, the electrical efficiency of the motor equipment will compare favorably with that of a similar direct-current equipment where one lead is always in circuit and no spark-preventing devices are employed. In other words, it is preferably to employ, so far as possible, the necessary resistances of the cable leads and to insert only such additional amount of resistance as may be found necessary. The object of introducing resistances into the conductors leading to each brush being to decrease the short-circuit current to a low and harmless value, it is evidently desirable to insert them in such a manner that the loss due to the passage of the normal load current will be as small as possible. One method of accomplishing this result is shown in Fig. 3, wherein the adjustable resistances r_1 , r_2 , are placed in the local leads l_1 , l_2 , connecting one of the machine terminals T, with the middle brush and the middle point of the reactance coil.

In the modification shown in Fig. 4, the reactance coil is divided and two leads are brought out from the middle, an adjustable resistance being inserted in each branch. It is obvious that the same effect will be produced if these resistances be placed between the brushes 1, 3, and the end terminals of the reactance coil. The reactance coils may be located at any convenient distance from the brushes of the machine and the connecting leads will serve as a resistance to limit the value of the short-circuit current, such additional resistance being inserted as may be found necessary and this may be varied at will during the operation of the machine.

By referring to Fig. 5, it will be seen that the brushes 1, 2, 3, may be arranged in staggered relation so that they may not be crowded together as they bear upon the commutator.

My method of preventing sparking is applicable to any type of alternating-current commutator machine, whether motor or generator and may be used with a single set of brushes or with a plurality of sets of brushes.

I claim as my invention:

1. The combination with an alternating-current machine, having a rotor provided with a commutator, of means for preventing sparking comprising a plurality of separate brushes at each point of commutation, connections between said brushes having means for producing a counter electro-motive force, and a plurality of leads from said brushes non-inductive at all times with respect to the normal current of the machine; substantially as described.

2. The combination with an alternating-current machine, having a rotor provided with a commutator, of means for preventing sparking comprising a plurality of separate brushes, connections between the brushes having self-contained means for producing a

counter electro-motive force and providing a plurality of inductive local circuits for the current due to the electro-motive force induced in the rotor coil short-circuited by the 5 brushes; substantially as described.

3. The combination with an alternating-current machine, having a rotor provided with a commutator, of means for preventing 10 sparking including a plurality of separate 15 brushes, connections between the brushes providing a plurality of local circuits for the current due to the electro-motive force included in the coil short-circuited by the 20 brushes, means in said connections whereby 25 reactance is opposed to the passage of current in the local circuits while offering a free 30 passage to the normal current of the machine, 35 said connections affording a plurality of leads from each point of commutation for the normal 40 current of the machine; substantially as described.

4. The combination with an alternating-current machine, having a rotor provided with a commutator, of means for preventing 25 sparking including a plurality of separate 30 brushes, connections between the brushes providing a plurality of local circuits for the current due to the electro-motive force induced in the coil short-circuited by the 35 brushes, an inductive resistance in one of 40 said local circuits, and a combined inductive and non-inductive resistance in another local circuit between said brushes; substantially 45 as described.

5. The combination with an alternating-current machine, having a rotor provided with a commutator, of means for preventing 50 sparking including separate brushes connected through a reactance device and another 55 other brush connected to an intermediate point in said reactance device, all of said 60 brushes being arranged to convey the normal current of the machine; substantially as described.

6. The combination with an alternating-current machine, having a rotor provided with a commutator, of means for preventing 65 sparking including separate brushes connected through a reactance device and another 70 other brush connected to an intermediate point in said reactance device through a non-inductive 75 resistance; substantially as described.

7. The combination with an alternating-current machine, having a rotor provided with a commutator, of means for preventing 80 sparking including separate brushes connected through a reactance device and another 85 other brush connected to an intermediate point in said reactance device through adjustable 90 non-inductive resistances, said connections being so arranged that the non-

inductive resistances are in series for the local currents and in parallel for the normal current of the machine; substantially as de- 65 scribed.

8. The combination with an alternating-current machine, having a rotor provided with a commutator, of means for preventing 70 sparking including a plurality of sets of separate brushes connected to the leads of the machine, each set having a reactance device connected between two of the brushes, and a non-inductive resistance connected between 75 an intermediate brush and an intermediate point in said reactance device; substantially as described.

9. The combination with an alternating-current machine, having a rotor provided with a commutator, of means for preventing 80 sparking including a plurality of sets of separate brushes connected to the leads of the machine, each set having a reactance device connected between two of the brushes, and 85 non-inductive resistances connected between an intermediate brush and an intermediate point in said reactance device, and a controller connected to said brushes through 90 said non-inductive resistances; substantially as described.

10. The combination with an alternating-current machine, having a rotor provided with a commutator composed of alternate live and dead segments, and sets of brushes therefor arranged to convey the normal 95 working current of the machine, each set including separate brushes locally connected through a reactance device and another brush connected to an intermediate point of the reactance device; substantially as de- 100 scribed.

11. The combination with an alternating-current machine, having a rotor provided with a commutator composed of alternate live and dead segments, of three separately 105 insulated brush units at each active point of commutation and a reactive connection between any two of said brush units; substantially as described.

12. The combination with an alternating-current machine, having a rotor provided with a commutator composed of alternate live and dead segments, of three separately 110 insulated brush units at each active point of commutation, each brush having a width less 115 than that of a dead segment and a reactive connection between any two of said brush units; substantially as described.

In testimony whereof I affix my signature in presence of two witnesses.
